MORRISON J. BARNETT, OF LOS ANGELES, CALIFORNIA, ASSIGNOR TO EBER BEAULIEU,
OF ALDERPOINT, CALIFORNIA.

CAMERA-SHUTTER-OPERATING DEVICE.

1,227,991.

Specification of Letters Patent.

Patented May 29, 1917.

Application filed March 18, 1916. Serial No. 85,098.

To all whom it may concern:

Be it known that I, MORRISON J. BARNETT, a citizen of the United States, residing at Los Angeles, in the county of Los Angeles 5 and State of California, have invented new and useful Improvements in Camera-Shutter-Operating Devices, of which the following is a specification.

This invention relates to improvements in 10 timers which operate to release a cable, actuate the shutter of a photographic camera, or, in general, any device of which the actuation is required to take place at a given time after being started, and the object of the invention 15 is to provide a device of this character which will be extremely simple in construction and easy and convenient of operation.

In the accompanying drawing, Figure 1 is 20 a longitudinal sectional view of the timer in the position in which it is ready for locking, and therefore ready to be engaged by a cable release; Fig. 2 is an end view of the same; Fig. 3 is a broken side view of the same, collapsed; Fig. 4 is a side view of the same 25 taken at right angles to Fig. 3; Fig. 5 is a broken side view of a cable release; Fig. 6 is a side view of a locking ring.

Referring to the drawing, 1 indicates a 30 cylindrical casing closed at one end by a head 2 and open at the other end, a pin 3 extending transversely through holes in the casing adjacent to its open end. A tubular traveler 4 within the casing can slide through said open end, said tube being closed 35 at the end within the casing by a head 6, there being secured to said head by a screw 7 and a washer 8 a cup leather 9 or a cup-shaped washer of other flexible material, thereby rendering the chamber 10 between 40 the heads 2 and 6 air-tight. When, however, the traveler is drawn out of the casing, as shown in Fig. 1, air is able to enter the chamber 10 between the two heads by means of a slight depression 11 in the inner surface of 45 the casing, which extends a short distance on both sides of the cup leather 9.

The traveler is limited in its outward movement by reason of the pin 3 engaging the inner ends of two diametrically opposite 50 longitudinal slots 12 in the tubular traveler, the inner ends of said slots extending transversely to their main direction, as shown at 13, and the traveler adjacent to said transverse extension being formed with slight 55 points or hooks 14, so that the inner end of

each slot is somewhat of the character of a bayonet slot. Stationarily secured within said tubular traveler by means of said pin 3 is a cylindrical abutment 16 between which and the head 6 is compressed a coiled 60 spring 17.

For the purpose of illustrating my invention, I have herein shown a release rod 18 connected to a cable 19 of a camera shutter, said release rod extending through a head 21 of a casing 22. Said head 21 is moved through the open end of the tubular traveler 4 until it is arrested by the inner surface of a circular groove 23 formed around said tubular traveler. It is then locked in that 65 position by means of a locking ring 24, which extends around the terminal portion of the tubular traveler in front of the head 21, and comprises a circular portion surrounding 70 said tubular traveler opposite to slots 26 cut 75 therein on opposite sides. Said ring comprises also a narrow rectangular extended portion 27 so that by moving said ring transversely across the tubular traveler, the sides 80 of said rectangular extension 27 can pass 80 through said slots 26 in the tubular traveler into the interior thereof and lock the head 21 of the casing of the release rod in the tubular traveler, in a position in which it 85 fits snugly against the inner surface of the groove 23. At this time, the release rod 18 is contained within the tubular traveler 4 and is adapted to be engaged by the side of the abutment 16 remote from the spring as soon as the head 6 has traveled inwardly in 90 the casing a sufficient distance to clear the depression 11 in the casing and has begun to compress the air in the chamber 10. For this purpose said side of the abutment is formed with a cavity 28 to receive the head 95 of the release rod.

The head 2 is formed with a minute vent hole 31 through which extends a needle valve 32 having a threaded stem 33 screwed in an enlarged hole 34 coaxial, and communicating, with the vent hole 31. To the outer end of the threaded stem is secured a spring metal arm 36 formed with an indenture 37 extending toward the head 2 of the casing, and adapted to enter any 100 one of a circular series, concentric with the head, of holes 38, the movement of the arm being limited by two stop pins 39, 40, driven into said head. By moving the arm in one direction, the screw is drawn outwardly 105 110

thereby enlarging the passage by which the air can pass through the hole 31 and by screwing it in the opposite direction the passage is contracted. It is evident by this 5 arrangement any desired speed of movement can be given to the air escaping from the chamber 10.

The operation is as follows:—The parts being in the position shown in Figs. 3 and 10 4, the tubular traveler is drawn outwardly, compressing the spring to the condition shown in Fig. 1, and is then turned, thereby locking the tubular traveler by means of the pin 3. The head 21 of the casing of 15 the release rod is then locked to the outer end of the tubular traveler in the manner before explained. The device is then ready for actuation. To actuate the device the casing 1 is turned relatively to the tubular 20 traveler 4 so as to release the tubular traveler from the restraining action of the pin 3. The spring 17 then immediately acts to move the tubular traveler 4 inwardly into the casing 1. This movement is rapid for 25 a short distance until the air is compressed within the casing. At about this time the head 21 of the release rod 18 is moved up against the stationary abutment 16 and its further movement is thereby arrested. 30 Since the casing 22 of the release rod, however, still moves with the traveler, the release rod itself moves relatively through the casing from right to left, when the parts are as shown in the drawing. The 35 duration of this movement is limited by the size of the opening through the vent hole 31 past the needle valve, which can be varied as desired by rotating the arm 36.

I claim:—

40 1. In a device of the character described, a cylinder closed at one end and open at

the other, said closed end having therein a circular series of recesses, a traveler traveling in said cylinder, means carried by the inner end of the traveler for forming a movable air-tight partition across the cylinder, a spring acting to move the traveler toward the closed end of the cylinder, means for securing an actuating device to the other end of the traveler, the closed 45 end of the cylinder having a vent hole therethrough, a needle valve screwed into said closed end and controlling said vent hole, and a spring arm secured to the outer end of said needle valve, and having means 50 for engaging any one of said recesses.

2. In a device of the character described, a cylinder closed at one end and open at the other, a tubular traveler traveling in said cylinder, means carried by the inner 55 end of the traveler for forming a movable air-tight partition across the cylinder, a spring acting to move the traveler across the closed end of the cylinder, said closed end having a vent hole therethrough, a 60 needle valve screwed into said closed end and controlling said vent hole, the outer terminal portion of the tubular traveler having a contracted portion, and the sides of said tubular traveler, outside or beyond 65 said contracted portion, being slotted, and a locking ring transversely movable in said slots and having a contracted portion for locking in said traveler the head of a 70 release rod casing.

75 In testimony whereof I have hereunto set my hand in the presence of two subscribing witnesses.

MORRISSON J. BARNETT.
